PUMP

Walter N. Huff, Harwood, Tex., assignor to Huff
Rodless Pump Company

Application October 8, 1935, Serial No. 44,114

1 Claim. (Cl. 103—44)

The present invention relates to new and useful improvements in pumps of the valved reciprocating piston type and has for its primary object to provide, in a manner as hereinafter set forth, a novel construction and arrangement whereby the usual rod extending from the piston to the surface of the ground is dispensed with.

Another important object of the invention is to provide a pump of the aforementioned character wherein the fluid being elevated is utilized for actuating the piston in one direction.

Other objects of the invention are to provide a pump of the character described which will be comparatively simple in construction, strong, durable, reliable in operation, compact, and light in weight.

All of the foregoing and still further objects and advantages of the invention will become apparent from a study of the following specification, taken in connection with the accompanying drawings wherein like characters of reference designate corresponding parts throughout the several views, and wherein:

Figure 1 is a vertical sectional view through a pump constructed in accordance with the present invention.

Figure 2 is a fragmentary view in vertical section, taken substantially on the line 2—2 of Figure 1.

Figure 3 is a fragmentary view in vertical section, taken substantially on the line 3—3 of Figure 1.

Figure 4 is a fragmentary view in vertical section, taken substantially on the line 4—4 of Figure 1.

Figure 5 is a horizontal sectional view, taken substantially on the line 5—5 of Figure 3.

Referring now to the drawings in detail, it will be seen that the embodiment of the invention which has been illustrated comprises an upper cylinder 1 with which a discharge pipe 2 communicates at an intermediate point. Slidable in the cylinder 1 is a piston 3 which is mounted on the lower end of a rod 4, said rod 4 extending slidably through a cap 5 on the upper end of said cylinder 1 for connection with suitable actuating means.

Threadedly connected to the lower end of the upper cylinder 1, and communicating therewith, is a tube 6. The reference numeral 7 designates a cylinder which is threadedly connected to the lower end of the tube 6 and which communicates therewith. Threadedly connected to the lower end of the intermediate cylinder 7 is a comparatively large lower cylinder 8 having mounted for

reciprocation therein a piston 9. The piston 9 is threadedly connected by a cage 10 to the lower end of a tubular rod 11 which extends upwardly through the intermediate cylinder 7 into the tube 6. A suitable check valve 12 in the cage 10 permits upward but not downward flow of fluid through the piston 9. Fixed on an upper portion of the tubular rod 11 and operable in the intermediate cylinder 7 is a piston 13. Of course, the tubing 6 and the tubular rod 11 may be of 10 as many sections and of any length desired.

As illustrated to advantage in Figure 3 of the drawings, a cage 14 is threadedly mounted on the upper end of the tubular rod 11 and operable in said cage 14 is a suitable check valve 15 which permits the fluid to flow into the tubing 6 from said tubular rod 11 but which prevents the return flow of said fluid. Threadedly engaged in the cage 14 and rising therefrom is a stem 16 having mounted on its upper end washers or the like 17. A coil spring 18 encircles the stem 16 and has its upper end engaged with the washers 17 and its lower end engaged with the lower end of the tubing 6.

In operation, the pump is normally filled with 25 fluid up to the piston 3. When the piston 3 is forced downwardly, the fluid between said piston 3 and the piston 13 forces the latter, together with the piston 9, downwardly, in a manner to compress the spring 18, during which stroke the 30 fluid below said piston 9 passes upwardly therethrough past the check valve 12. Then, when pressure on the piston 3 is removed, the coil spring 18 expands, raising the pistons 13 and 9 and causing the fluid above the piston 9 to be elevated through the tubular rod 11, through the tubing 6 and into the upper cylinder 1 from which it is discharged through the pipe 2. Of course, this operation is then repeated, the piston 3 again being forced downwardly to lower piston 9 against 40 the tension of the spring 18, etc. As the piston 3 moves downwardly the discharge pipe 2 is shut off from communication with the lower portion of the cylinder 1 and the tubing 6 thereby.

It is believed that the many advantages of a 45 pump constructed in accordance with the present invention will be readily understood, and although a preferred embodiment of the device is as illustrated and described, it is to be understood that changes in the details of construction and in the 50 combination and arrangement of parts may be resorted to which will fall within the scope of the invention as claimed.

What is claimed is:—

A pump comprising an upper cylinder having a 55

discharge, a piston operable in said upper cylinder, means for actuating said piston, a tube connected to said upper cylinder and depending therefrom, an intermediate cylinder connected with the lower 5 end of the tube and communicating therewith, a comparatively large lower cylinder connected to the lower end of the intermediate cylinder and communicating therewith, a valved piston operable in the lower cylinder, a tubular stem connected to the second-named piston and extending 10 upwardly therefrom into the intermediate cylinder, said tubular stem communicating, at its lower end, with the lower cylinder and at its

upper end with the tube, a piston fixed on the tubular stem and operable in the intermediate cylinder, the first-named piston constituting means for forcing the third and second-named pistons downwardly through the medium of the 5 fluid between said first and said third named pistons, a check valve for preventing downward flow of the fluid through the tubular rod, a stem rising from the upper end of said tubular rod, and a coil spring encircling said stem and opera- 10 tively connected thereto for elevating the second and third named pistons.
